UNITED STATES PATENT OFFICE.

FRED STARR, OF CHICAGO, ILLINOIS.

DESIGN FOR A CLIP.

SPECIFICATION forming part of Design No. 25,017, dated December 31, 1895.

Application filed November 21, 1895. Serial No. 569,740. Term of patent 14 years.

To all whom it may concern:

Be it known that I, FRED STARR, a citizen of the United States, residing at Chicago, in the county of Cook and State of Illinois, have invented and produced a new and original Design for Clips; and I do hereby declare the following to be a full, clear, and exact description of the invention, such as will enable others skilled in the art to which it appertains to make and use the same.

The accompanying drawing illustrates in perspective a clip made in accordance with my new design.

Referring to the drawing, A is intended to indicate the clip as a whole, and *a a'* its two arms. These arms are spaced apart, as shown in the drawing, and are brought together at a point slightly in rear of their free ends, as at *b*, and the free ends are slightly divergent, as at *c*.

The distinguishing characteristic of the de-

sign is the circular or disk-like enlargement B of one arm of the clip about midway of its length, which enlargement is cut away at the points *d*, giving the same an appearance resembling a Maltese cross, or as having segmental pieces *e e* projecting laterally from opposite sides of the arm, and other segmental pieces *f f* midway between the first-mentioned pieces, out from which latter the two parts of the arm project, the design being such that notches are left between the segmental pieces *e* and *f*.

Having thus described my design, I claim—
The design for a clip, substantially as shown and described.

In testimony whereof I affix my signature in presence of two witnesses.

FRED STARR.
